UNITED STATES PATENT OFFICE.

WILLIAM A. PEEK AND WALLACE E. DUNKERLEY, OF HELENA, MONTANA.

PRESSURE REGULATING AND EQUALIZING VALVE.

1,187,385.

Specification of Letters Patent. Patented June 13, 1916.

Application filed February 12, 1915. Serial No. 7,780.

To all whom it may concern:

Be it known that we, WILLIAM A. PEEK and WALLACE E. DUNKERLEY, citizens of the United States, residing at Helena, in the 5 county of Lewis and Clark and State of Montana, have invented new and useful Improvements in Pressure Regulating and Equalizing Valves, of which the following is a specification.

10 This invention relates to a pressure regulating and equalizing valve for hot water heating systems, designed for use in the relief pipe extending between the boiler and the expansion tank.

15 The primary object of the invention is to provide a valve which will operate to hold the pressure in the boiler and system to any desired degree, and which, when such pressure is exceeded, will open and allow the 20 water to flow to the expansion tank, the valve also operating upon a reduction of pressure in the boiler or system to a degree less than the pressure due to the head of the water in the expansion tank to connect 25 the portions of the system between which the valve is arranged to secure an equalization of pressure.

A further object of the invention is to provide a valve for the purpose described which 30 operates as a combined pressure regulating and equalizing check valve, which may be readily and conveniently cleaned, repaired and adjusted to vary the working pressure, and which is composed of comparatively 35 few parts not liable to easily get out of order.

The invention consists of the features of construction, combination and arrangement of parts herein fully described and claimed, 40 reference being had to the accompanying drawing in which:—

Figure 1 is a view in elevation showing the valve arranged in the relief pipe of a hot water heating system. Fig. 2 is a vertical 45 longitudinal section through the valve.

In carrying our invention into practice, we provide a valve casing 1 having internally threaded inlet and discharge ports 2 and 3, respectively, and an intermediate partition 4 provided with a port or passage 5, and sub-dividing the interior of the casing into influx and efflux chambers. The port or passage 5 is controlled by an annular regulating valve 8 having a seat flange 9 movable upwardly against a seat 10 formed upon the partition 4, and having a depend-

ing retaining flange 11 which extends into the upper end of a conical pressure regulating spring 12, whereby the valve is normally held against its seat. The passage in the 60 downwardly opening pressure regulating valve member 8 is controlled by an upwardly opening equalizing check valve 13 which has a beveled face 14 arranged to close against a seat 15 on the said valve member 8, the 65 check valve being provided with a stop boss or lug 16 arranged to abut against the boss or lug 17 on the valve casing whereby the upward movement of the valve member 13 is limited.

The spring 12 seats at its lower end upon a supporting and adjusting head 18 carried by a stem 19 having an externally projecting angular end 20 to receive a wrench or like tool, whereby said stem may be turned or 70 rotate. The stem is threaded as at 21, to engage internal threads on a stuffing box 22 having a guide chamber 23 in which the adjusting head moves and having adjacent thereto an annular flange 24 fitting within 75 a groove or recess in a threaded depending portion 25 of the valve casing, whereby the stuffing box is fitted in operative position. A threaded retaining nut 26 engages the threaded portion or extension 25 and the 80 flange 24 and detachably holds the stuffing box in position, the lower end of the stuffing box being threaded to receive a gland or packing nut 27 retaining suitable packing 28, whereby leakage of water is prevented. 85

The valve is arranged in practice between the sections 29 and 30 of the relief pipe of a hot water heating system, the section 29 constituting a pressure pipe leading from the boiler and the section 30, a relief and equalizing pipe leading to the expansion tank, 90 between which pipes the valve 1 is arranged. In the pipes cut-off valves 31 are also placed on opposite sides of the pressure regulating and equalizing valve 1, so that when it is 100 desired to clean or repair the valve 1 the valves 31 may be closed, whereupon the nut 26 may be removed and the internal parts of the valve disconnected and detached for cleaning, repairs or renewal as occasion may 105 require.

It will be understood that the valve member 8 may be adapted by regulating the pressure of the spring to retain any desired pressure within the boiler and system, it being 110 understood that said valve will be held closed by the spring until the determined

2
pressure in the boiler and system is exceeded, whereupon the valve 8 will open under the excess pressure on the boiler side and allow the water to flow to the expansion tank, whereby relief is afforded, the valve however closing after affording such relief in order to maintain the proper working pressure. This pressure may be increased or diminished by adjusting the tension regulating member 18 up or down to vary the resistance of the spring 12 to the opening movement of the valve, as will be readily understood.

When at any time the pressure in the boiler or system is reduced to a degree less than the pressure resulting from the head of the water in the expansion tank, it will be evident that the water in the tank will force open the valve member 13 allowing the water to flow from the expansion tank side or section of the relief pipe to the boiler side thereof, by which the pressures on opposite sides of the valve will be equalized and the water permitted to fill up the boiler and system. As soon as the pressure is equalized again, the valve member 13 will close by gravity and the pressure upon the boiler side, thus tending at all times to maintain substantially uniform working pressures and conditions.

30 We claim:—

A valve of the class described comprising a casing having aligned influx and efflux connections and an intervening partition pro-

vided with a port having a valve seat, said 35 partition separating the interior of the casing into inner and outer chambers communicating with the respective connections, a ported regulating valve controlling the port in the partition and adapted to open under the pressure through the influx connection, a gravity check valve controlling the port in the regulating valve and adapted to open in a direction toward the influx connection, said check valve being fitted and movable 40 within the regulating valve and having a projection, a stop within the casing in the path of said projection for limiting the opening movement of said check valve, a head movable within the outer chamber and provided with an annular flange, a stem 45 connected with the head and having a portion in threaded engagement with the casing and an exteriorly projecting annular end, and a coiled conical spring having its 50 reduced end bearing on said head and surrounded by said annular flange and having its enlarged end bearing against the ported valve, said valve having a flange fitting within the enlarged end of the spring. 55

60 In testimony whereof we affix our signatures in presence of two witnesses.
